UNITED STATES PATENT OFFICE

JOHN A. BOHNSACK, OF CLEVELAND HEIGHTS, OHIO, ASSIGNOR TO THE E. F. HAUSER-MAN COMPANY, OF CLEVELAND, OHIO, A CORPORATION OF OHIO

PANEL UNIT

Application filed September 17, 1927. Serial No. 220,119.

The present improvement relates to the construction of a movable panel unit for metallic building structures and is especially desirable for a panel unit containing glass because a panel unit made according to this invention can be shipped, stored, erected or moved without disturbing the putty, in other words it is completely glazed.

It is among the objects of this invention to provide a construction which is simple and convenient for manufacture, strong and durable, consisting of few parts and pleasing in appearance, especially by the avoidance of exposed welded joints. Other objects and advantages will appear as the description proceeds.

The invention consists of the features hereinafter described and particularly pointed out in the claims; the following description and the annexed drawings setting forth but one illustrative embodiment of the various forms in which the principle of the invention may be applied.

In said annexed drawings:—

Fig. 1 is a perspective view of a panel unit constructed according to this invention.

Fig. 2 is a vertical section thru upper horizontal member of such unit.

Fig. 3 is a horizontal section thru the joint between the stile and chair rail being parts of such unit.

Fig. 4 is a fragmentary broken perspective view of the joint shown by Fig. 3.

The figures disclose panel unit 1, being shown for convenience as containing one glass panel 2 and one steel panel 3, and having vertical stiles 5, upper horizontal member 4, chair rail 6 and bottom rail 9.

Each vertical member or stile 5 is formed with a deep U shaped longitudinally extending panel holding groove 7. Said stile 5 has cleats 8 (see Figs. 3 and 4) struck up on the panel facing side at the locations desired fitting within the cross members 4, 6, 9 of the panel unit 1 and thereby preventing either the rotation or dislocation of said cross members either laterally or vertically with respect to the stile. Holes are provided in the bottom of the aforementioned panel holding grooves 7 in the stiles 5 at suitable locations

for tie rod bolts 10, so located as to be concealed within the boundaries of the cross members 4, 6, 9.

By locating said tie rod bolts 10 at each cross member 4, 6, 9 it is possible by drawing up on said bolts to produce tight joints between the interfitted ends of the cross members 4, 6, 9 and the face of the stile 5, it being noted that in this construction illustrated such ends require simply to be square cut in order to obtain a perfect joint. In other words, the construction here shown is desirable because there is no necessity for mitering any joints between stile and cross members. Furthermore the tie rod bolts bind the panel unit together in a strong, durable and inexpensive manner without the use of welding, brazing, seaming or riveting and the bolts as previously stated are entirely concealed. The panel unit may remain bolted together during shipping, storage, erection or moving; but if due to accident it is desired to replace any one or more elements of said panel unit or if it is desirable to change the width or composition of said panel unit, the bolts may be removed and such replacement or substitution made on the job by comparatively unskilled labor and at low cost.

Wiring holes 11 are provided thru the stile 5, opening into the space within the cross member 4, 6, 9 to allow the insertion of electric wires whenever desired in any section whatever of the panel unit 1. Since these wiring passages should be of greater diameter than the width of the groove 7, and it is not desirable to weaken the stile, these holes or passages are formed by embossing or expanding the edges of the groove outwardly at such point, as shown in Fig. 4. This provides a strong construction without loss of metal.

To provide for conveniently reglazing said panel unit 1, when necessary, the upper horizontal member 4 of all glazed panel openings is bipartite, constructed of a fixed portion 4 and a frictionally retained removable molding portion 12 (see Fig. 2).

To insert a glass panel 2 in a panel unit 1, having removed the molding 12, the glass 2 is inserted in the before-mentioned deep U

shaped groove 7 in one stile 5 whereupon the glass 2 can be swung into alignment with the panel holding groove in the chair rail 6 and lowered into said groove. The glass 2 can then be adjusted laterally so as to be brought into engagement an equal amount with the panel holding grooves 7 in both stiles 5; the deep U-shaped groove 7 having provided room enough for the admission of sufficient width of glass for that purpose. The molding 12 is then pressed into position and the putty applied.

Inasmuch as one of the chief purposes of a glazed partition is to transmit light, a glazed panel unit constructed according to this invention is especially useful because the stiles thereof are narrow and consequently present a minimum of obstruction to light and because of the rigid construction of said panel units they may be installed as close to one another as desirable even without the interposition of a stud therebetween.

While the partition unit as illustrated in Fig. 1 has stiles vertically disposed with horizontal cross members, it obviously is a matter of indifference, so far at least as certain of the foregoing features of improvement are concerned, whether such be the disposition of the parts in question or whether such disposition be reversed. So, too, the unit may comprise a single panel 2 or 3, or more such panels, the number of cross-members being correspondingly decreased or increased.

The tie rod bolt 10 as shown is threaded at both ends and has nuts applied thereto. This construction may of course be varied by having one end of the rod formed into a head or bent over in the form of a hook.

Other modes of applying the principle of this invention may be employed instead of that explained, change being made as regards the features herein disclosed, provided the means stated by any of the following claims or the equivalent of such stated means be employed.

I therefore particularly point out and distinctly claim as my invention—

1. In a metallic partition assembly, units comprising channel-shaped sheet metal verticals presenting grooves; grooved hollow horizontal cross members extending between positioning cleats on the web portions of such verticals, one of such horizontals presenting a movable portion to allow insertion of a stretcher in such grooves; tie rods extending between the web portions of such verticals; and wiring holes leading from within such horizontals through the verticals and formed by lateral displacement of the walls of the vertical grooves.

2. In a metallic partition; units comprising panel plates, sheet metal channel frame verticals each having a groove, hollow horizontals extending between the verticals on opposite sides of the panel plates and clamped

between the verticals by tie rods; and holes extending through such verticals into such hollow horizontals said holes being formed by re-forming the side walls of the groove to a greater width than the groove. 70

3. In a metallic partition construction; panel units consisting of channel-shaped sheet metal verticals with grooves and projections on their web portions; hollow horizontal cross members positioned against said verticals by means of said projections; and wiring holes leading into such horizontals and of greater width than the grooves and formed without destruction of the parallel walls of the grooves. 75 80

4. In metallic partition construction; panel units comprising channel-shaped sheet metal verticals having grooves on their web portions; hollow horizontal cross members extending between the web portions of such verticals; tie rods within said cross members and clamping them between the web portions of such verticals; and holes leading from the interior of such horizontals through the web portions of such verticals and traversing the grooves, said holes being wider than the grooves and formed by displacement of the walls of the grooves. 85 90

5. In metallic partition construction; vertical channel members having flanges and grooved webs; horizontal hollow groove-providing members engageable between webs of pairs of said vertical channel members; panel members carried by the grooves in said vertical channel members and said horizontal members; and wiring holes leading from the interior of such horizontals through the grooves in said verticals, such holes being of greater width than the grooves and formed by displacement of the walls of such grooves. 95 100 105

Signed by me this 13 day of September, 1927.

JOHN A. BOHNSACK.
